US00D571560S

(12) **United States Design Patent**
Liu et al.

(10) **Patent No.:** **US D571,560 S**
(45) **Date of Patent:** **** Jun. 24, 2008**

(54) **DISPLAY**

(75) Inventors: **Ching-Chi Liu**, Taipei (TW);
Wen-Chang Tsai, Kaohsiung Hsien
(TW)

(73) Assignee: **Universal Scientific Industrial Co., Ltd.** (TW)

(**) Term: **14 Years**

(21) Appl. No.: **29/279,885**

(22) Filed: **May 10, 2007**

(51) **LOC (8) Cl.** **06-07**

(52) **U.S. Cl.** **D6/300; D14/126; D14/345**

(58) **Field of Classification Search** **D6/300-314;**
40/714, 700, 716, 152.1, 906, 124.03, 721,
40/722, 735, 737-739, 790, 798, 800, 717,
40/455, 457; **D14/126, 129, 345, 496, 374,**
D14/341, 375; D10/2, 75
